UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,246,754.

Specification of Letters Patent. Patented Nov. 13, 1917.

Application filed May 22, 1916. Serial No. 99,057.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, and more particularly to linotype machines of the general organization represented in United States Letters Patent No. 436,532 to O. Mergenthaler, wherein circulating matrices are released from a magazine or magazines in the order in which their characters are to appear in print and then assembled in line, the composed line transferred to the face of a mold, the mold 15 filled with molten metal to form a slug or linotype against the matrices which produce the type characters thereon, and the matrices thereafter returned through distributing mechanism to the magazine or magazines 20 from which they started.

In these machines, the matrices are usually conducted from the distributing mechanism to the magazines by channeled members known as "magazine entrances," and 25 such entrances are pivoted so that they may be swung backwardly and downwardly from their operative positions for inspection or to give access to the distributing mechanism and the magazines. It frequently happens, for one reason or another, 30 that matrices become lodged in the entrances, and consequently, when the latter are turned down, the trapped matrices slide out of their open ends onto the floor or into 35 the machine, causing annoyance and inconvenience and in some cases injury to the matrices or the mechanism.

It is the object of my present invention to avoid these difficulties, and to that end 40 specifically I provide the swinging entrance with a tray which when the entrance is lowered will stand in position to catch any matrices falling therefrom.

In the accompanying drawings, I have 45 shown my invention only in preferred form and by way of example, but many changes and variations may be made therein and in its mode of application which will still be comprised within its spirit. Generally 50 speaking, I desire it to be understood that I

do not limit myself to any specific form or embodiment, except in so far as such limitations are specified in the claims.

Referring to the drawings:

Figure 1 is a side elevation of the upper 60 portion of a linotype machine having my invention applied thereto;

Fig. 2 is a section on the line 2—2 of Fig. 1; and

Fig. 3 is a section on the line 3—3 of 65 Fig. 2.

The drawings have been limited to those elements of the machine directly concerned with my invention, the other parts of which may be of the usual or any well-known construction. In the present instance, I have illustrated my improvements as applied to a double-magazine machine, the particular arrangement of which forms no part of my present invention except in the respects to 70 be hereinafter noted.

In this machine, the matrices after casting are delivered to a font-separating mechanism (not shown) which sorts them according to font and delivers them to one or 80 the other of the distributing mechanisms B and C suitably supported in the machine frame A. The two distributing mechanisms separate the matrices according to character and drop them into the entrances D, E, 85 through which they pass into one or the other of the magazines F, G. The magazine entrances are both mounted in a common supporting frame H, which is pivoted to the machine frame A, as at H¹, so as to be swung 90 backwardly and downwardly from their operative position, all in the usual way.

In carrying out my invention, I attach to the swinging frame H a tray or trough J arranged in position to catch any matrices 95 which may slide out of the upper ends of the two entrances when the latter are lowered by the pivotal movement of their supporting frame. Thus, as shown in Fig. 1, the tray is attached to the upper end of the 100 supporting frame H, and stands upright when the frame is in operative position. When, however, the frame is swung down, as shown by the dotted lines, the tray is carried therewith and caused to assume a 105 substantially horizontal position, where it will catch any matrices passing from the upper ends of the entrances.

Inasmuch as it may be desired at times to view the matrices in course of distribu- 110

tion or to gain access to the distributors without moving the entrances from their operating position, I have mounted the tray J upon the supporting frame H so that it 5 may be swung downward at will to an inoperative position thereon. To this end, the tray is attached to supporting sleeves J¹ which are pivotally mounted upon a transverse rod H³ supported by brackets H⁴ secured 10 to the entrance-frame H. The tray is held in its upright or operative position on the frame by fixed clips H². These clips are adapted to enter enlarged elongated notches J⁴ in the lower side flange of the 15 tray and are engaged with and disengaged from the end walls of the notches by shifting the tray longitudinally to the right and left, respectively, upon its supporting rod H³. Thus, in Fig. 2, the tray is shown in 20 its position to the right with the clips H² overlapping the walls of the notches J⁴, the tray thus being locked against pivotal movement. However, by shifting the tray to the left, as indicated by the arrow and dotted 25 lines in Fig. 2, the notches J⁴ are brought into complete registry with the holding clips, which are thus disengaged from the tray, and the latter is then free to be swung downward to the dotted line position shown 30 in Fig. 1. In the present instance, a spring J² tends constantly to move the tray to and hold it in its locked position, the spring bearing at one end against the leftmost supporting bracket H⁴ and at its opposite end 35 against the adjacent bearing sleeve J¹ of the tray. In returning the tray to its operative position, therefore, it is shifted to the left against the action of the spring so as to bring the notches J⁴ into registry with 40 the holding clips H², and then, when the tray is released, the spring shifts it to the right and effects its locking engagement with the clips H².

It will be observed that unless the tray 45 is thus shifted to the left when swung upwardly, it cannot be returned to its upright or operative position, due to the engagement of its lower side flange with the holding clips H², which can only enter the flange-notches J⁴ when the tray occupies its position to the left. The spring thus serves not only to maintain the tray in locked position, but requires it to be locked before it can remain in its upright or operative position.

55 The tray is provided with a finger ring J³ to facilitate its operation, and as the tray, when in operative position, is positively connected to the entrance frame H, the latter may if desired be swung downward by means 60 of the finger ring.

While I have illustrated the use of the tray in connection with two separate magazine entrances, it will be understood that it will be equally as serviceable when applied 65 to a single entrance or to a greater number.

It will also be understood that the particular form of tray illustrated has been selected merely by way of example and as the preferred form. Obviously many modifications and alterations of the invention and 70 in its mode of application will suggest themselves to those skilled in the art without departure from its scope.

Having thus described my invention, its construction and mode of operation, what I 75 claim and desire to secure by Letters Patent of the United States is as follows:

1. In a typographical machine, the combination of a magazine, distributing mechanism therefor, an intermediate magazine 80 entrance movable into and out of operative relation to said parts, and matrix holding means carried by the entrance, said means in the operative position of the entrance being arranged free and clear of the distributing mechanism and in the inoperative position of the entrance arranged to receive matrices falling therefrom.

2. In a typographical machine, the combination of a magazine, distributing mechanism therefor, an intermediate magazine entrance pivotally mounted so as to be swung upwardly and downwardly into and out of operative position, and a matrix catch tray carried by the entrance at its upper 90 end, said catch tray being arranged in the operative position of the entrance upright behind and clear of the distributing mechanism, and adapted by the downward movement of the entrance to be presented in a 95 horizontal position to receive matrices falling from the upper end thereof.

3. In a typographical machine, the combination of a magazine, distributing mechanism therefor, and an intermediate magazine entrance movable at will from its operative position, the said entrance being provided with a matrix catch tray which is 100 mounted thereon so as to be movable to an operative or an inoperative position as desired.

4. In a typographical machine, the combination of a magazine, distributing mechanism therefor, an intermediate movable magazine entrance provided at its upper 115 end with a matrix catch tray movable at will to operative or inoperative position thereon, and releasable locking means to hold the tray in its operative position.

5. In a typographical machine, the combination of a magazine, distributing mechanism therefor, an intermediate movable magazine entrance provided at its upper end with a matrix catch tray movable at will to an operative or inoperative position thereon, and locking means to hold the tray in its operative position, the said locking means adapted to be disengaged by an endwise movement of the tray.

6. In a typographical machine, the com-

- 5 combination of a magazine, distributing mechanism therefor, an intermediate movable magazine entrance provided at its upper end with a matrix catch tray pivotally connect-
 ed thereto and shiftable longitudinally thereon, and a device engaging the tray to hold it against pivotal movement, the said device being disengageable by the endwise shifting of the tray.
- 10 7. In a typographical machine, the combination of a magazine, distributing mechanism therefor, and an intermediate movable magazine entrance provided at its upper end with the matrix catch tray J, whose lower side flange is formed with the notches J⁴, the transverse supporting rod H³ upon which the tray is pivotally mounted and also longitudinally shiftable, and the holding clips H² adapted to enter the notches J⁴ in the tray and to be engaged with and disengaged from the tray by its endwise movements in opposite directions.
- 15 8. In a typographical machine, the combination of a magazine, distributing mechanism therefor, and an intermediate movable magazine entrance provided at its upper end with the matrix catch tray J, whose lower side flange is formed with the notches J⁴, the transverse supporting rod H³ upon which the tray is pivotally mounted and also longitudinally shiftable, the holding clips H² adapted to enter the notches J⁴ in the tray and to be engaged with and disengaged from the side flange of the tray by its endwise movements in opposite directions, and the spring J² tending constantly to move the tray in a direction to effect its engagement with the holding pieces H², substantially in the manner shown and described.
- 20 9. In a typographical machine, the com-
 bination of a magazine, distributing mechanism therefor, and an intermediate movable magazine entrance provided at its upper end with a pivotally mounted matrix catch tray shiftable longitudinally thereon, locking means adapted to be engaged with or disengaged from the catch tray by the endwise movement of the latter, and a spring tending constantly to shift the tray longitudinally in a direction to effect its engagement with the locking means.
- 25 10. In a typographical machine, the combination of a magazine, distributing mechanism therefor, and an intermediate movable magazine entrance provided at its upper end with a pivotally mounted matrix catch tray shiftable longitudinally thereon, and locking means to hold the tray in its operative position, said locking means acting to prevent the return of the tray to its operative position until it is first shifted endwise.
- 30 11. In a typographical machine, the combination of a magazine, distributing mechanism therefor, and an intermediate movable magazine entrance provided at its upper end with a pivotally mounted matrix catch tray shiftable longitudinally thereon, locking means to hold the tray in its operative position, said locking means acting to prevent the return of the tray to its operative position until it is first shifted endwise in one direction, and a spring acting when the tray is located in its operative position to shift it in the opposite direction to effect its engagement with the locking means.

In testimony whereof, I have affixed my signature.

DAVID S. KENNEDY.
